UNITED STATES PATENT OFFICE

HARRY W. JONES, OF WEBSTER GROVES, MISSOURI, ASSIGNOR TO SANFORD INVESTMENT COMPANY, OF WILMINGTON, DELAWARE, A CORPORATION OF DELAWARE

RAILWAY CAR

Application filed February 25, 1930. Serial No. 431,152.

This invention relates to railway cars in which the bottom is movable for discharging the lading. It relates particularly to such cars having a bottom door or a plurality of 5 bottom doors hinged on a horizontal line or lines transverse to the length or course of travel of the car.

In such cars heretofore manufactured, provision is made for holding the door or doors 10 in the closed position and for releasing the doors to allow them to turn downward on their hinges to permit discharging the lading by gravity.

Among such means a latch mechanism has 15 been used for engaging the rear end of the door, if there was only one door, and to engage the rear end of the rear door when a plurality of doors were made a part of the car.

20 The object of this invention is to provide a stronger and more effective mechanism for engaging the rear end of such a door when that door has been raised approximately into the horizontal, closed position.

25 As an example of such a car heretofore manufactured, reference is here made to Letters Patent of the United States, No. 1,512-, 059, granted to Hugh W. Sanford, Oct. 21, 1924, for "railways". In that patent, an arm 30 extends rearward from the rear edge of the door and is engaged by hooks on downward-directed arms which are supported to be moved pendulum-fashion transversely to the length of the car.

35 In this application, my improvement is shown applied to such a car having only one such door.

In the accompanying drawings,

40 Fig. 1 is an elevation of the right hand side of a mine car embodying my improvement;

Fig. 2 is a section along the upright, middle, longitudinal plane of the car;

Fig. 3 is a similar section showing the door released;

45 Fig. 4 is a transverse, upright section on the line, 4—4, of Fig. 1, looking toward the right;

Fig. 5 is an enlarged detail elevation of the mechanism shown on the rear part of Fig. 1, 50 adjacent the line, 4—4;

Fig. 6 is a longitudinal upright section on the line, 6—6, of Fig. 4, looking toward the left;

Fig. 7 is a detail plan of the oscillating 55 arm, shown in Fig. 5;

Fig. 8 is a longitudinal, upright detail section illustrating the support for the forward end of the door;

Fig. 9 is a rear view of the structure shown 60 by Fig. 8;

Fig. 10 is a cross section on the line, 10—10, of Fig. 7.

Referring to said drawings, A, A are track rails, resting on cross ties, A1. B, B are ordinary car wheels applied to the ends of the 65 axles, C, C, which extend transversely across the body of the car. D, D are side walls. E, E are end walls of the car.

G is a shaft extending across the car body 70 horizontally and parallel to the inner face of the forward end sill of the car and having its ends resting in the side walls, D, D.

H is the bottom door. This extends beneath the axles, C, C and fills the space between the side walls. The forward end of 75 the door extends to the shaft, G, and is secured thereto by hinge straps, H1, surrounding said shaft and riveted to the bottom of the door. At each side edge, said door has an upward-directed flange, H2, which serves 80 to stiffen the door and to allow the door to extend below the lower edges of the side walls. The flanges, H2, extend only near enough to the walls, D, to allow free up and down movement of the door. The body of 85 the door is low relative to the height of its up-curved ends.

The drawings show a bar or plate, H4, applied to the lower face of the door, along 90 the rear edge of the door, and secured to the door by bolting or riveting or soldering. Said plates serve to take wear, as described further on, and to stiffen that part of the door. The lower face of that plate is to be 95 engaged by my improved means for holding the door in the approximately horizontal closed position.

The upper part, D1, of each side wall of the car leans outward, and the lower part, 100

D, of each of said walls is upright, and has a lower outward-directed flange, D2.

At the rear end of the door a bearing, I, is placed against the outer face of the adjacent part, D, of each side wall and near the flange, D2, and secured to said wall by bolts or rivets, I1. Each side wall is apertured opposite the bore of the adjacent bearing. A bearing bushing, I2, extends through the bearing, I, and the adjacent part of the wall, D, and has at the inner face of said wall an annular flange, I3, resting against said inner face. The interior of said bushing is polygonal in cross section (the drawings show it square). Said bushings are free to turn in the bearing, I.

A rock-shaft, J, of polygonal (square) cross section adapting the shaft to engage said bushings extends from one bearing, I, 20 to the other and into the bearing bushings. At the right hand side of the car, said shaft extends through the bearing, I, and supports a hub, J1, said hub surrounding said shaft and fitting the four sides of said shaft and 25 fixed thereon by keying or similar means. On said hub is an arm, J2, reaching obliquely outward away from the car and forward. (Figs. 1, 4, 5 and 7). The outer face of said arm is channeled and receives a bar, J3, 30 rigidly secured to said arm by bolts or rivets, J4. The outer end of the bar, J3, is bent horizontally away from the car to form an arm, J5, which is to be engaged by a stationary cam along the track, as will be described further on.

At each bearing, I, a washer, J6, surrounds the bearing bushing beside the bearing, I. At the outer face of the washer, a cotter, J7, extends through the bushing and the shaft, 40 J. Thus each bushing is held against endwise movement toward the car, while the flange, I3, on the bushing holds the bushing against movement away from the car. By extending the cotter through the shaft, the 45 shaft is held against endwise movement in the bushing, I3, and the bearing, I. Because the shaft is four-sided and the bushings are fitted to the shaft, the shaft can not rock independently of the bushings. When the 50 shaft rocks, the bushings rock with the shaft, the bushings rocking in the bearings, I.

The common axis of the bearings, I, and the shaft, J, is in a horizontal plane which is lower than the wearing plate, H4, on the 55 door, H, and said axis is far enough rearward in said plane to make space between the shaft, J, and the wearing plate, H4, for a hub, L1, and a cam-form lateral extension, L, resting on said shaft, said hub surrounding and being fitted to the faces of said shaft, J, for seating said hub immovably on the shaft.

One such extension is shown placed near each flange, I3, of each bearing bushing, I2. 60 Between these extensions other hubs, L1 and

L, may in similar manner be placed on the shaft, J, as may be desired to give the rear end of said door, H, ample support. If the door is not large and the loads carried thereby are not heavy, a single extension between the bearings will be sufficient. When the door is closed, each extension, L, is directed toward the wearing plate, H4. Each face, L3, of said extension is approximately parallel to the adjacent face of said plate, H4, when the door rests on said extension. At each side of the face, L3, the face of the extension has a rounded or curved part, L4, to meet the faces, L5, which extend to the hub, L1. A wearing plate, L6, of approximately uniform thickness is seated over the faces, L3 and L4, and a part of the forward face, L5, of the extension. 70 75 80

When the door is in the closed position, the plate, H4, rests on the part, L3, of the plate, L6. To release the door, the shaft, J, is turned contra-clockwise as viewed in Figs. 1 and 5 and clockwise, as shown in Fig. 6, to turn the extension rearward to allow a clear downward path for the end of the door.

Flattening the extension face is for the purpose of bringing the support of the wearing plate, H4, nearer the axis of the shaft than is the adjacent forward part of the extension. This difference in the facing of the extension prevents the extension from turning rearward without lifting the door and the load of coal or other material supported by the door. Thus provision is made for automatically keeping the extension in engaged position until it is desired to release the door by forcibly rocking the shaft, J. In practice, I have found that flattening the face, L3, of the extension to a depth of one-eighth of an inch is sufficient to make the desired degree of engagement with the door to keep the cam from turning excepting through turning strain applied to the shaft, J. 90 95 100 105

An angle bar, E1, is applied to the rear part of the lower face of the wall, E, close to the position of the rear end of the door when the door is closed. One flange of said bar is placed flatwise against the wall, E, and is riveted to said wall. The other flange of said bar extends rearward and downward from the upper part of the other flange. Thus the bar is applied to the end wall as a means of stiffening the lower edge of said wall. At the same time sufficient sheltered space is left under and behind said wall to receive the extension or extensions, L, when the door is to be released. It will be noted that when the door is closed and the car body is filled with coal or other material, this space for receiving the extensions will be clear of coal. Accordingly, when the door is to be released, the extension-receiving space is clear and receives the cam member in such manner as to prevent the discharging 110 115 120 125 130

coal from resting on the extensions. This extension-receiving recess or chamber is to be kept in mind when studying the operation of this mechanism.

- 5 It is to be understood that, when stiffening the end wall is not desired, the angle bar, E1, may be omitted. But, in such case, the adjacent part of the wall, E, will afford a sheltered space for the extensions, L.
- 10 At the tipple or other place for discharge, a stationary lifting cam, M, is seated on cross ties, A1, beside the track, in the path of the outer end of the horizontal arm, J5, of the bar, J3, so that during forward movement 15 of the car, the arm, J5, will meet said lifting cam and ride upward on said cam, whereby the rock-shaft, J, is given a partial turn contra-clockwise, as viewed in Fig. 5, whereby the extension, L, is turned rearward out 20 of engagement with the end of the door, H, and into the cam recess or chamber above described.

A stirrup, E2, is suspended from the body wall, D1, (Figs. 1 and 5) in position to allow 25 the arm, J5, of the bar, J3, to reach outward through said stirrup into position to meet the lifting cam, M. The stirrup extends downward into position to arrest the downward movement of the arm, J5, when 30 the extension, L, is in its operating position. The rear, upright part of the stirrup is in position to limit upward movement of the arm, J5, the purpose being to prevent said arm from rising much more than is needed 35 to release the lifting cam, M.

The weight of the arm, J5, and the bar, J3, and the hub arm, J2, is intended to be sufficient to cause downward turning when the arm, J5, is free from the lifting cam, M. 40 That freeing is to be so timed as to occur after the rear end of the door has moved downward beyond the extensions, L, and the hubs, L1.

After the material has been discharged 45 from the car and the door has become free to be again lifted into the closed position, that lifting may be accomplished manually or by any suitable means located along the track, as, for example, a cam rail located between the track rails as disclosed in Letters 50 Patent of the United States, No. 1,268,390, granted to Hugh W. Sanford, June 4, 1918.

While the rear end of the door is being pushed upward it will bear against the face 55 of the plate, L6, on the extensions, L3, and turn said extensions backward until the end of the door has passed said extensions. Thereupon the weight of the arm, J5, and the bar, J3, and the hub arm, J2, causes movement of said members downward until the arm, J5, engages the lower part of the stirrup, E2, that movement causing the rocking of the shaft, J, far enough to bring the extensions, L, into operating position against the 60 lower face of the wearing plate, H4, on the

door. Thus the door is again in the locked position ready to receive another load.

In the foregoing, the shaft, J, has been illustrated and described as projecting through the right hand bearing, I, and there receiving the hub, J1, the arm, J2, and bar, J3, for rocking the shaft, J.

It is to be noted that this shaft is adapted to be reversed to make it project from the left hand bearing, I, and there receive the hub, J1, the arm, J2, and bar, J3. For this no change need to be made in the shaft or bar. The washers, J6, and the cotters, J7, are to be applied as shown in Fig. 4.

It has already been stated, that heretofore, 380 in a similar car, a hook arm, supported pendulum-fashion above the rear end of the door, brought its hook into engagement with an arm extending rearward on the rear edge of the door. In that structure the arm is a 385 suspension or hanger member on which the rear door is hung or suspended.

In my improved form, each extension, L2, extends upward from the shaft, J, and serves as a prop for supporting the end of the door; 390 and said prop is turned rearward to disengage it from the door, whereby the door is made free to fall by gravity.

For further contrast with prior art, and to emphasize the nature of the structural combination which I have formed, attention is invited to the fact that the hook arm supported pendulum-fashion, could not be substituted for the rockable prop structure forming a part of my improvement. The slanting 400 end wall, E, placed rearward of the rear end of the door precludes placing the pendulum-form hook to serve for engaging the door. To give the car more capacity, it is desirable to slant each end wall as much as will permit 405 sliding of the coal when the door is down for discharge of the coal.

In the foregoing description, I have stated that a plurality of hubs and extensions may be placed to engage the door. When that is done, the rock shaft and the hubs and extensions constitute a rocking member making extended engagement with the rear part of the door.

While my drawings show only one bottom door, it is to be understood that my invention is applicable when there are several bottom doors. In a car of large capacity, a plurality of doors are ordinarily desirable.

I claim as my invention:

1. In a car of the kind described, the combination with side walls, of a door located between said walls and having its forward end hinged on an axis which is horizontal and transverse to said walls, bearings on an axis which is horizontal and transverse to said walls and rearward of and below the rear end of the door when the door is closed, a door supporting rock-shaft resting in said bearings and having an upward extension 125 130

adapted to be rocked under and against a part of the door when the door is closed, and means supported by said shaft outside the car and adapted to be engaged for rocking said shaft.

2. In a car of the kind described, the combination with side walls, of a door located between said walls and having its forward end hinged on an axis which is horizontal

10 and transverse to said walls, bearings on an axis which is horizontal and transverse to said walls and rearward of and below the rear end of the door when the door is closed, a door supporting rock-shaft resting in said 15 bearings and having a plurality of upward extensions adapted to be rocked under and against a part of the door when the door is closed, and means supported by said shaft outside the car and adapted to be engaged for 20 rocking said shaft.

3. In a car of the kind described, the combination with side walls, of a door located between said walls and having its forward end hinged on an axis which is horizontal 25 and transverse to said walls, bearings on an axis which is horizontal and transverse to said walls and rearward of and below the rear end of the door when the door is closed, a polygonal door supporting rock-shaft having 30 an upward extension adapted to be rocked under and against a part of the door when the door is closed, bearing bushings fitted around said shaft and resting in said 35 bearings, and means supported by said shaft outside the car and adapted to be engaged for rocking said shaft.

4. In a car of the kind described, the combination with side walls, of a door located between said walls and having its forward 40 end hinged on an axis which is horizontal and transverse to said walls, bearings on an axis which is horizontal and transverse to said walls and rearward of and below the rear end of the door when the door is closed, a door supporting rock-shaft resting in said 45 bearings and having an upward extension adapted to be rocked under and against a part of the door when the door is closed, and an arm supported on said shaft outside the 50 car and adapted to be engaged for rocking said shaft.

5. In a car of the kind described, the combination with side walls, of a door located between said walls and having its forward end hinged on an axis which is horizontal 55 and transverse to said walls, an end wall at the rear of the rear end of the door, bearings on an axis which is horizontal and transverse to said walls and rearward of and below the rear end of the door, when the door is closed, and below said end wall, a door supporting 60 rock-shaft resting in said bearings and having an upward extension adapted to be rocked under and against a part of the door when the door is closed, and means outside 65

the car and supported by said shaft and adapted to be engaged for rocking said shaft.

6. In a car of the kind described, the combination with side walls, of a door located between said walls and having its forward end hinged on an axis which is horizontal and transverse to said walls, an end wall at the rear of the rear end of the door, bearings on an axis which is horizontal and transverse to said walls and rearward of and below the rear end of the door, when the door is closed, and below said end wall, a door supporting rock-shaft resting in said bearings and having a plurality of upward extensions adapted to be rocked under and against a part of the door when the door is closed, and means outside the car and supported by said shaft and adapted to be engaged for rocking said shaft.

7. In a car of the kind described, the combination with side walls, of a door located between said walls and having its forward end hinged on an axis which is horizontal and transverse to said walls, an end wall at the rear of the rear end of the door, bearings on an axis which is horizontal and transverse to said walls and rearward of and below the rear end of the door, when the door is closed, and below said end wall, a door supporting polygonal rock-shaft having an upward extension adapted to be rocked under and against a part of the door when the door is closed, bearing bushings fitted around said shaft and resting in said bearings, and means outside the car and supported by said shaft and adapted to be engaged for rocking said shaft.

8. In a car of the kind described, the combination with side walls, of a door located between said walls and having its forward end hinged on an axis which is horizontal and transverse to said walls, and a rock-shaft on an axis which is horizontal and transverse to said walls and downward and rearward of the rear end of the door when the door is in the closed position and said rock-shaft having a lateral flattened extension adapted to engage the lower face of the rear part of the door.

9. In a car of the kind described, the combination with side walls, of a door located between said walls and having its forward end hinged on an axis which is horizontal and transverse to said walls, and a rockable prop structure transverse and perpendicular to said walls and extending outward beyond the side of the car and adapted to be rocked downward into position to engage the lower face of the rear end of said door and to be turned upward out of the path of said door.

10. In a car of the kind described, the combination with side walls, of a door located between said walls and having its forward end hinged on an axis which is horizontal and transverse to said walls, and a rockable prop

structure adapted to be rocked into position to engage the lower face of the rear end of said door and to be turned out of the path of said door, said rockable structure extending 5 through one of said walls and being there accessible to be engaged for rocking.

11. In a car of the kind described, the combination with side walls, of a door located between said walls and having its forward end 10 hinged on an axis which is horizontal and transverse to said walls, a rearward sloping end wall at the rear of the rear end of the door, and a rockable structure placed horizontally and transversely to the side walls 15 and upright in position below the end wall and at the rear of the path at the rear end of the door in position to be turned downward to engage the door when the door is in the closed position.

12. In a car of the kind described, the combination with side walls, of a door located between said walls and having its forward end 20 hinged on an axis which is horizontal and transverse to said walls, and a rockable prop structure transverse and perpendicular to said walls and adapted to be turned downward into position to make extended engagement with the lower face of 25 the rear end of said door and to be turned upward out of the path of said door.

13. In a car of the kind described, the combination with two side walls, of a door located between said walls and having its forward 30 end hinged on an axis which is horizontal and transverse to said walls, and a rockable prop structure supported on an axis transverse and perpendicular to said walls and extending outward beyond the side of 35 the car and said structure being shaped and adapted to be rocked to move its working face in a segmental path which is above the horizontal plane of the axis of said structure and which path extends into the path of the rear 40 end of said door.

14. In a car of the kind described, the combination with side walls, of a door located between said walls and having its forward end 45 hinged on an axis which is horizontal and transverse to said walls, a rockable prop structure transverse and perpendicular to said walls and adapted to be turned downward into position to engage the lower face of the rear end of said door and to be turned 50 upward out of the path of said door and said rockable prop structure extending outward beyond the side of the car, and an arm supported by said outer end of the rockable prop structure and extending forward of said structure 55 when said structure is in position to engage and hold the door.

15. In a car of the kind described, the combination with side walls, of a door located between said walls and having its forward end 60 hinged on an axis which is horizontal and

transverse to said walls, a rockable prop structure transverse and perpendicular to said walls and adapted to be turned downward into position to engage the lower face of the rear end of said door and to be turned upward out of the path of said door and said rockable prop structure extending outward beyond the side of the car, an arm supported by said outer end of the rockable prop structure and extending forward of said structure when said structure is in position to engage and hold the door, and means for limiting downward turning of said arm.

16. In a car of the kind described, the combination with side walls, of a door located between said walls and having its forward end 70 hinged on an axis which is horizontal and transverse to said walls, and a rockable prop structure transverse and perpendicular to said walls and adapted to be turned downward into position to engage the lower face of the rear end of said door and to be turned upward out of the path of said door and said prop structure having a lateral extension presenting a flattened face against which the lower face of the rear part of the door will 75 rest when the door is in the closed position and the prop structure has been turned downward.

In testimony whereof I have signed my name this 18th day of February, in the year one thousand nine hundred and thirty.

HARRY W. JONES.
